METHOD AND MACHINE FOR MAKING
WIRE-DRAWING DIES, ETC.

John E. Peterson and Emil A. Van Beke, North Bergen, N. J., assignors to Eisler Electric Corporation, Newark, N. J., a Corporation of Delaware

Application July 21, 1930. Serial No. 469,381

2 Claims. (Cl. 51—33)

Our invention relates to drilling, forming and polishing holes in hard substances and materials such as diamonds and other precious and semi-precious stones, glass, refractory metals and other materials where it is necessary to have the holes drilled or formed or polished or to have any combination of drilling, forming and polishing. The invention is useful among other respects for making drawing- or squirting-dies or other articles comprising a perfectly round, uniformly formed and polished hole whose containing wall may have any contour such as cylindrical, conical, convex, etc.

The method in common use for drilling, forming and polishing holes in such materials consists in drilling the hole through the material with a drill-point of steel or other suitable metal and using a drilling powder of diamond dust or other hard material; and then in separate operations coning the front and back of the hole; and polishing and finishing it. These operations, performed in separate stages, require a separate set-up of the machine and the work-piece for each stage, with resulting inaccuracies in the form of the hole as well as loss of time.

The method and machine of our present invention accomplishes all of the above and other important operations in a single set-up of the machine and of the work-piece to produce a perfectly formed and polished hole.

The accompanying drawing shows diagrammatically one preferred embodiment of a machine within our invention; and said drawing and the following description serve to illustrate the invention but without limiting the invention to the details thereof except as called for by the claims.

In the drawing, Fig. 1 is a front elevation of the machine; Fig. 2 is a side view thereof; Fig. 3 is the same as Fig. 1 except that the rotary table and related parts are shown in vertical cross-section and the tilting head is shown only in its vertical or middle position, also the polishing wire and its connections are shown; and Fig. 4 is an enlarged view in vertical cross-section of a portion of the turntable and the drawing-die shown in the other figures in which the hole is being drilled in accordance with our invention, said figure serving to illustrate the co-action of the drill with the work-piece at various times as the work progresses as will be hereinafter explained.

The machine in general comprises a drill spindle 1 suitably supported so as to be tilted from a vertical position into an angular position rela-

tively to the work-piece A, and further comprises a rotary table 2 for the support of the work-piece to be drilled, formed and polished; and further comprises a specially constructed hollow spindle 3 for supporting the rotary table having combined therewith means for receiving a wire 4 through the hollow of the spindle, the lower end of said wire being swivelled and yieldingly attached to a fixed part of the underneath framework of the machine, and its upper end, which projects through the hollow spindle and the hole in the work-piece, being secured in the chuck 5 of the drill spindle so that the wire rotates with the spindle.

Only a portion of the stationary framework 6 of the machine is shown. A bracket 7 secured to this framework supports the bearing 7^a of the turntable spindle. This turntable spindle is a hollow tube 3 which has an outwardly extending flange or shoulder 3^a at its upper end overlying the upper end of the bearing 7^a. Its lower end projecting below the bearing supports a pulley 8 keyed thereto. The rotary turntable 2 has a center hole through it in communication with a hole through a hollow stem 2^a integral with the bottom of the turntable. In the particular form shown, this stem is conical and is fixed in the mouth of a tube 3^b contained within the previously described hollow spindle 3. There is a sliding fit between this tube and the spindle; and means is provided for longitudinally adjusting the tube and, therefore, the turntable which it supports for a limited distance up and down in the hollow spindle, said adjusting means comprising screw-threads 3^c on the outside of the tube in engagement with other screw-threads on the inside of the rotary spindle. This adjusting means further comprises a knurled head 3^d on the tube by which the operator of the machine can screw the slide tube 3^b into and out of the rotary spindle 3 to a greater or less extent and so adjust the height of the turntable to any desired position relatively to the drill. Means not necessary to illustrate may be provided to maintain said adjustments when made.

The drill head for operatively supporting the drill consists of a bracket 9 of any suitable or preferred form which, however, at its lower end at the general level of the cutting end of the drill is pivotally supported at 9^a from the framework 6 of the machine so that the entire head can be caused to sway laterally from side to side or to occupy any suitable angular position between the vertical position shown by the full lines in Fig. 1 and the dotted lines in the same figure

in order to adjust correspondingly the angular position of the drill B relatively to the work-piece in boring a hole therethrough and in forming and shaping the walls of said hole. Massive 5 lateral extensions 9^a—9^c from the drill-head adjacent the pivot 9^a lower its center of gravity and tend to prevent vibration.

The drill head 9 is provided as shown with two spaced apart arms 9^b to support aligned bearings which in turn operatively support the drill spindle 1 whose lower end is provided with the usual chuck 5 for the drill. A pulley 10 is secured by set-screw 10^a to the drill spindle between the arms 9^b of the head for driving the spindle. The set-screw permits the pulley to be raised and lowered relatively to the toe of the rock-arm 18.

Means, not necessary to illustrate, is provided for driving respectively the drill spindle and the 20 turntable spindle, the former by means of the belt 11 engaging the grooved pulley 10 and the latter by the belt 12 engaging the grooved pulley 8 previously described. These speeds may be varied in practice but we have found that a speed 25 of 1000 R. P. M. for the drill spindle 1 and a speed of 200 R. P. M. in an opposite direction for the turntable 2 gives good results. These speeds may be varied in accordance with the type of the material to be worked. The revolving of the 30 material to be drilled in an opposite direction from and simultaneously with the drill-point has been found to have an advantageous effect in producing a perfectly round, formed and polished hole.

35 It will be understood that the drill-spindle 1 can move vertically while rotating in its bearings; and that it is given sufficient weight so that it constantly tends to force the drill against the work with the requisite pressure.

40 Means is provided when desired for continuously swaying or oscillating the spindle head about its pivot 9^a through an arc which is adjustable as to its length or throw. For this purpose, when it is desired to use it, the machine 45 comprises a crank-driven connecting-rod 14 whose ends are pivotally connected respectively to the upper part of the drill-head and to the crank pin. The crank illustrated takes the form of a rotary disk 15 or wheel supported for rotation in suitable bearings by the frame of the machine and having suitable driving connections thereto for rotating it comprising a worm-wheel 21 fixed to or rotatable with the disk 15 and a belt and pulley-driven worm 22. The crank pin 50 15^a forms part of a block 15^b which is slideable across the face of the disk between a pair of guides 15^c and is securable in any desired position of adjustment along said guides to vary the throw of the crank and the oscillation-arc of the 55 drill-head.

60 In addition, means is provided which automatically and intermittently raises and lowers the drill spindle and the drill relatively to the turntable and the work-piece while the machine is in operation. This up and down motion takes place many times during each sway of the spindle-head. The means comprises a rotary cam 16 suitably supported on the side of the drill-head driven by a 65 motor means (not shown). This cam engages the heel of a rock-arm 18 pivoted intermediate its ends to the drill-head with its toe 18^a extending under the drive pulley 10 on the drill spindle, which latter, it will be understood, is slideable up and down in its bearings. Thus, for each rotation

of the cam, the drill spindle and the drill will be raised by the rock-arm and then lowered by the previously referred to means that gives it downward tendency, such as the weight of the drill-spindle. This intermittent raising and lowering 80 of the operative end of the drill relatively to the work is for the purpose of freshening the drilling powder at the work and to provide a rubbing effect by the drill on the hole that is being formed. This automatic raising and lowering of the drill spindle takes place simultaneously with its own rotation and the rotation of the work-piece and with the controllable and adjustable swaying of the drill-head; and thereby enables the wall of the hole to be formed with the desired contour. The extent of this up and down motion may be 85 adjusted by using the set-screw 10^a of the pulley 10 to adjust the position of the pulley relatively to the toe of the rock-arm 18.

90 The die or work-piece A to be drilled is secured or mounted on the turntable 2 in any desired or preferred manner; and comprises the usual metallic casing A¹ rigidly enclosing the diamond or other hard substance A² which is to be drilled and formed into the die, etc. A hole having been 95 bored through the top of the metallic casing A¹ with any suitable machine tool down to the diamond A², the work-piece is then centered on and affixed to the turntable with said hole uppermost. The crank pin 15^a is then adjusted to the 100 center of its disk or approximately so. The knurled head 3^d is operated to adjust the height of the turntable and the work-piece as well as the height of the drill B and the drill spindle 1 resting upon it so that the up and down motion delivered 105 by the rock-arm 18 is minimized. Suitable abrasive powder having then been applied, the machine is set in motion and the oppositely rotating drill and work-piece drill a vertical hole in the diamond. Gradually more and more sway is 110 imparted to the drill head by suitably adjusting the position of the crank pin. Also, the extent of the up and down movement of the drill spindle and drill is increased.

115 Fig. 4 shows in cross-section a completely 120 drilled, formed and polished die A² producible by this machine in a single set-up. The lead-in cone on the front of the die can be varied in slope and contour by suitably adjusting the throw of the crank and the oscillation-arc of the drill 125 spindle. B' and B² in Fig. 4 indicate two of the many positions of the tool during its up and down and laterally swaying movements to form the lead-in cone. The over-all size and depth of the 130 cone is also under control, including the adjustment of the height of the turntable by means of the knurled head 3^d. The drilling and polishing of the wall of the hole may be carried out by disconnecting the swaying attachment and operating the drill spindle as a simple revolving 135 spindle simultaneously with the other devices. The drilling, forming and polishing of the relieving-cone on the back of the die is provided by suitably adjusting and operating the swaying attachment of the drill spindle; and two of the positions of the tool are shown at B' and B³ in Fig. 4 when forming this cone. Similarly, holes having other contours may be formed by appropriate 140 operation of the machine to operate the drill in positions corresponding to those required by the 145 desired wall-contour.

145 On some material it is highly desirable to polish out the hole. Therefore, means is further provided usable whenever desirable for polishing and 150 finishing the interior surface of the hole with a

rotary wire 4. After the hole has been bored through the work-piece and it is ready for polishing by this method, the wire 4 is passed through the hollow turntable spindle and through the 5 hole in the work-piece. The upper end of the wire is secured in the chuck of the drill spindle; and its lower end is secured to the rotary member 19^a of a swivel whose outer relatively stationary part 19 is secured to a coiled tension 10 spring 20 attached to a portion of the underneath framework of the machine. The machine is then set in motion, whereupon the wire is rapidly rotated about its own axis and is brought into rubbing contact with the walls of the hole in the 15 work-piece by the lateral swaying of the drill head; and moreover, at the same time the wire is caused by the rock-arm 18 to slide up and down in contact with the wall of the hole as permitted by the spring 20. The net result of all 20 of these motions is highly efficient polishing action by the wire upon the wall of the hole. This operation of finishing the surface of the hole can also be accomplished in other ways,—for example, by not rotating the drill spindle or the wire 25 and by rotating only the turntable and the work-piece; or vice versa by rotating the drill spindle and the wire but holding stationary the work-piece and the turntable; or by the combination of the two as at first described.

30 The illustrated machine shows only a single-unit drill spindle. However, in practice, multiples of the devices shown have been combined in one machine with interconnections between them whereby ten or more work-pieces can be 35 drilled simultaneously by a single operator.

It will be noted that the turntable has an axial hole or opening 2^a in continuation of or under the hole through the die or other article which is being formed so that the point of the tool B 40 during the up and down and swaying movements of the tool can play freely through the hole in the work-piece into the turntable opening without any interference therewith. In this way, both the entering and the relieving cones of the 45 hole in the work-piece may be formed by suitably

changing or regulating the swaying and other movements of the tool relatively to the work-piece but without changing the original set-up of the work-piece on the turntable which is adapted to remain the same throughout.

It will be understood that changes and modifications will be made in the illustrative embodiment of our invention without, however, departing from its scope and spirit.

What we claim is:

1. In combination, a rotary work supporting table and means for rotating it, a pivotally supported drill head and means for oscillating it on its pivot axis, and a drill spindle journaled in the drill head transverse to the pivot axis of the drill head and being furthermore mounted to be reciprocated in the drill head, and a tool carried by the spindle and extending across the pivot axis of the drill head to have a double coning operation on the work-piece without changing the set-up thereof, assisted by the relative rotation of the spindle and the work table and the oscillation of the drill head and spindle.

2. In apparatus for drilling and reaming work-pieces without resetting the latter, the combination with a rotatable work supporting table having an axial opening therethrough and means for rotating the table, of a drill head capable of lateral oscillation on an axis transverse to the axis of and substantially at the level of the table, a drill spindle journaled in the head and laterally movable with the same, said spindle being reciprocable toward and from the table, means for rotating the spindle, means for fixing the drill head with the spindle substantially perpendicular to the work supporting table and in line with the opening therein to permit the work on the table to be drilled, and for oscillating the work head while the table is rotated to cause the said work to be reamed by the spindle after it has been drilled.
